[57] ABSTRACT

In an electrostatographic imaging surface blade cleaning system in which a cleaning blade is cyclically translated laterally of the normal direction of motion of the imaging surface between two substantially spaced apart translation end dwell positions, an irregular multi-lobe cam blade drive is provided for the cyclic lateral translation of the cleaning blade and also for automatically multiply slightly shifting the blade end dwell positions on the imaging surface without requiring a major decrease in their maximum available spacing.

2 Claims, 3 Drawing Figures

PATENTED DEC 17 1974

3,854,814

FIG. 1

FIG. 2

FIG. 3

TRANSLATING DWELL CLEANING SYSTEM

The present invention relates to electrostatographic imaging surface blade cleaning systems, and in particular to such a system providing changes in the end dwell positions of a translating cleaning blade.

A problem in the use of cleaning blade systems for cleaning moving xerographic photoreceptor imaging surfaces of imaging material has been the tendency of blade edge sealing failures, such as localized tuckunders, to occur at points where the blade edge is being repeatedly struck at the same point by the same defects on the imaging surface being repeatedly rotated past the blade edge while the blade edge is stationary. Cyclic translation movement of the cleaning blade transverse the direction of the photoreceptor has been previously found to avoid most of these problems, especially if the translation continues after the imaging surface stops and a short dwell-time drive cam is used, (and especially if the imaging surface is buffed). U.S. Pat. Nos. 3,724,019 and 3,724,020 cited below relate to such translation mechanisms. However, if simple lateral translation during machine operation is used, there will be two fixed position end dwell positions on the photoreceptor at which the blade stops at the same place to reverse in each translation cycle. Thus, in these two dwell points the blade is not fully protected by translation from the above-described single point multiple impacts from the same defects on the photoreceptor. Another approach to blade translation is disclosed in U.S. Pat. No. 3,740,789 and the "3100" machine cited below. This involves moving the blade in a series of short separate steps in each direction of major translation. However, this results in a large number of dwell points for each full blade translation cycle. The present invention provides a solution to the above-described problem by a simple means for cyclically shifting the two end dwell points of a continuous blade translation system without substantially affecting the full available translation stroke length, thereby providing an increased effective lifetime for the blade.

Exemplary xerographic photoreceptor blade type dry toner cleaning apparatus, to which the present invention relates, is disclosed in U.S. Pat. Nos. 3,438,706 issued Apr. 15, 1969, to H. Tanaka et al.; 3,552,850 issued Jan. 5, 1971, to S. F. Royka et al.; 3,634,077 issued Jan. 11, 1972, to W. A. Sullivan; 3,660,863 issued May 9, 1972 to D. P. Gerbasi; 3,724,019 issued Apr. 3, 1973 to Alan L. Shanly; 3,724,020 issued Apr. 3, 1973 to Henry R. Till; and 3,740,789 issued June 26, 1973 to Raymond G. Ticknor. Pending applications include U.S. Applications Ser. No. 356,985, filed May 3, 1973, by Richard E. Smith (D/73001) and Ser. No. 356,986, filed May 3, 1973, by Christ S. Hasiotis (D/73196). Toner cleaning systems with a translating polyurethane cleaning blade are commercially embodied in the Xerox Corporation "4000" and "3100" xerographic copiers. The present invention is an improvement in this technology, and accordingly these references are hereby incorporated by reference in the present specification.

The present specification embodiment discloses a specific improvement in the xerographic cleaning blade translation structure disclosed in the above-incorporated U.S. Pat. Nos. 3,724,019 and 3,724,020 and the Xerox "4000" copier, requiring only a modification thereof comprising changing the drive cam con-

figuration and speed to provide the desired multiple shifting of the blade translation end dwell positions. This modification may also, however, eliminate the need for the additional structure for continuing the blade translation after machine stoppage taught by these same two patents. In view of the existing teaching provided by these two patents, there is no need in the following specification description to discuss the common and associated features and structures in any detail.

Further features and advantages of the present invention pertain to the particular apparatus and functions whereby the above-mentioned aspects of the invention are attained. Accordingly, the invention will be better understood by reference to the following description and to the drawings forming a part thereof, which are substantially to scale, wherein:

FIG. 1 is a plan view of an exemplary embodiment of the present cleaning blade system;

FIG. 2 is an enlarged detail of the drive cam and cam follower from FIG. 1; and

FIG. 3 is an alternative embodiment of the drive cam and cam follower of FIGS. 1 and 2.

Referring now to the drawings, FIGS. 1 through 3, and first of the embodiment of FIGS. 1 and 2, there is shown therein an exemplary blade cleaning system 10 in accordance with the present invention for cleaning toner from the photoreceptive imaging surface 12 of a xerographic drum 14. The surface 12 is cleaned by a contacting cleaning blade 16 extending transverse the direction of movement (rotation) of the imaging surface 12. The present invention relates particularly to a blade drive system 20 for laterally oscillating the cleaning blade 16 back and forth across the imaging surface 12, as illustrated by the arrow in FIG. 1.

The blade drive system 20 provides improved cleaning blade life and reliability by, in addition to translating the cleaning blade, also shifting or translating the two end dwell positions in which the cleaning blade 16 stops at the end of each lateral extreme of the blade oscillation. These two dwell points have been found to be the initial failure points of the blade when only simple blade translation is provided. The blade drive system 20, utilizing a multilobe cam drive, shifts or moves these end dwell positions by a small distance in each cycle to substantially increase the number of dwell positions and thereby assist in extending the effective cleaning blade life.

The cleaning system 10 here is the same as that disclosed in the two above-referenced U.S. Pat. Nos. 3,724,019 and 3,724,020, except for the provision of a multi-lobe cam 22 and the preferred use of a lower cam rotational speed. As in these two reference patents, the cam 22 is driven about a fixed axis of rotation 24 at a relatively slow speed by a conventional small electric motor 26 and conventional integral gear reduction unit. However, the cam of these two reference patents is a heart-shaped single-lobe cam, whereas the cam 22 is multi-lobed. As far as the cam 22 rotational speed, if the same approximate blade translational speeds are to be utilized as in the system described in these two patents, the gear reduction from the motor 26 should be increased approximately in proportion to the increase in the number of cam lobes.

Similarly to the two above-referenced patents, the rotation of the cam 22 causes the lobes of the cam 22 to push upwardly on one arm of an engaging cam fol-

lower 28, which thereby oscillates about its own pivotal axis 30. An equal length arm of the cam follower 28 on the opposite side of the axis 30 from the cam engaging arm is pivotally secured to, and linearly moves, a pull rod 32. The pull rod 32 in turn is directly connected for translation to the cleaning blade 16. The pull rod 32 thereby pulls the cleaning blade 16 toward the drive system 20 during the rise or lift portion of the cam surface movement toward the cam lobe apex. The return motion of the cleaning blade is provided by a coil spring 34 under tension pulling on the opposite side of the cleaning blade 16 mounting, in opposition to the pull rod 32.

The above-described operation of the blade drive system 20, and particularly the configuration of the multilobed cam 22, is best seen in FIG. 2. It may be seen that the particular exemplary cam 22 here has five flat faceted lobes, which are sharply peaked or pointed at their apexes for minimum blade dwell times at the lobe peaks. It may be particularly seen that each of the cam lobes has a different maximum (apex) distance or radius of revolution from the axis 24 of rotation of the cam 22. These distances are shown, for example, for the highest cam lobe by the arrow "A" and for the lowest cam lobe by the arrow "B". They correspond directly to the positions of one of the two end dwell points. The minimum cam surface radius between each lobe corresponds to the other end dwell point, and it may be seen that these are all different also.

Each lobe of the cam 22 provides a full oscillation of the cleaning blade 16 for substantially as great a distance as could be provided by a single lobe cam, and with no substantial increase in the dwell times. However, each lobe here has different maximum and minimum radii of revolution about the axis 24 and therefore provides slight shifting or cyclic changes of both of the two translation end dwell positions of the blade. This shifting occurs automatically in response to, and as a part of, the blade oscillation, without any stopping of the blade motion between the two dwell positions. The cleaning blade 16 does not step transversely across the imaging surface 12 in small steps from one side to another. Rather, it fully cyclically traverses to substantially the maximum practical and usable extent in each cycle with each cam lobe.

Although not essential, a desirable additional feature provided by the drive system 20 is the irregular spacing in angular and circumferential distance of the cam lobes around the axis 24. This provides a cyclic changing of the blade translation speed and total translation time for each cam lobe, which is desirable. The more irregular the motion, the less likely is that the blade translation can occur sequentially or harmonically with the rotation of the drum 14.

It may be seen that the blade drive system 20 can increase the number of pairs of different (shifted) dwell points in direct proportion to the increase in the number of cam lobes. The five lobe cam 22 increases to 10 the number of different dwell points, and no dwell positions of adjacent blade oscillations are the same. They are spaced apart in time by four intervening oscillations. Thus, it may be seen that the tendency for blade failures to occur in proportion to the time spent in a given dwell position is substantially reduced. Yet, it will also be observed that this is accomplished here without necessarily substantially decreasing the overall blade stroke length, i.e. the translation distance between the

two end dwell positions of the blade. The stroke length can, of course, be changed as well, if desired, by appropriate design of the cam surface, but it is not necessary with the disclosed system to sacrifice the utilization of a large percentage of the maximum stroke length between the most extreme allowable end dwell positions.

Considering now the alternative cam and cam follower embodiment of FIG. 3, it may be seen that this Figure discloses a different cam 40 with a different shaped cam surface. This cam surface has more rapid drops following the peaks of the cam lobe to provide a more rapid blade return by the spring 32. The cam 40 also provides a reduction in the dwell times of the dwell positions corresponding to the cam recesses. If desired, an even more extreme configuration can be used, such as a saw tooth shape which would allow a fly-back return for helping to break up excessive toner, lubricant, or contaminant build-up on the cleaning blade edge. In other respects, the embodiment of FIG. 3 is similar in structure and operation to that of FIGS. 1 and 2 described above.

Merely as exemplary of suitable blade translation speeds but not limited thereto, a blade translation velocity of between approximately 0.5×10^{-4} centimeters per second and 0.2 centimeters per second is appropriate for cleaning with distributed blade wear. Likewise, an amplitude of oscillation (distance between dwell points) of greater than approximately 0.15 centimeters but not extending off of the imaging surface is suitable.

Various other modifications or improvements will be apparent to those skilled in the art, although the exemplary embodiments described herein are presently considered to be preferred. The following claims are intended to cover all variations and modifications as fall within the true spirit and scope of the invention.

What is claimed is:

1. An electrostatographic imaging surface blade cleaning system in which a cleaning blade is cyclically oscillated laterally of the normal direction of motion of the imaging surface between two substantially spaced apart translation end dwell positions of said blade on said imaging surface, wherein the improvement comprises a blade drive means for cyclic lateral oscillation of said cleaning blade and for automatically multiply slightly shifting the positions on said imaging surface of said two blade translation end dwell positions without stopping the blade motion between said two translation end dwell positions,

wherein said blade drive means comprises a multi-lobe cam rotatably driven about an axis of rotation and a cam follower driven by said multi-lobe cam, said cam follower being drivingly connected to said blade for cyclic translation of said blade by said cam, and wherein said multi-lobe cam has a plurality of cam lobes having different maximum and minimum radii of revolution about said axis for said automatic shifting of said two blade translation end dwell positions at each said cyclic translation of said blade by said cam.

2. The system of claim 1, wherein said cam lobes are also irregularly spaced angularly around said axis with respect to one another to cyclically change the speed of said blade translation.
